Primary Examiner — T. Chase Nelson*Assistant Examiner* — Ania Aman*(74) Attorney, Agent, or Firm* — Edward P Dutkiewicz**CLAIM**

The ornamental design for a motor wedge, as shown and described.

DESCRIPTION

FIG. 1 is a top plan view of the motor wedge showing my new design. The phantom lines depict exemplary environmental indicia, which forms no part of the claimed design;

FIG. 2 is a bottom plan view thereof;

FIG. 3 is a left side elevational view thereof;

FIG. 4 is a right side elevational view thereof. Note that the right side view is a mirror image of the left side view;

FIG. 5 is a wide end side view thereof; and,

FIG. 6 is a narrow end side view thereof.
